UNITED STATES PATENT OFFICE.

GASTON LEINEKUGEL LE COCQ, OF CHÂTEAUNEUF-SUR-LOIRE, FRANCE.

HANGAR FOR DIRIGIBLES.

1,347,815.

Specification of Letters Patent. Patented July 27, 1920.

Application filed February 28, 1918. Serial No. 219,683.

To all whom it may concern:

Be it known that I, GASTON LEINEKUGEL LE Cocq, at Châteauneuf-sur-Loire, Department of the Loiret, France, citizen of the 5 French Republic, have invented certain new and useful Improvements in Hangars for Dirigibles; and I do hereby declare the following to be a full, clear, and exact description of the invention, such as will enable 10 others skilled in the art to which it appertains to make and use the same.

The present invention has for its object a hangar for dirigibles consisting in the arrangement of four girder poles supporting 15 two main suspension girders constituted by cables or chain bars supported by these four girder poles, the said main suspension girders carrying the ends of the main stays of secondary and transverse girders which 20 with the covering constitute the roof which is independent of the walls and the vertical and lateral partitions of the hangar erected in the form of traveling doors which can be moved on rails and constitute a form of 25 outer harbor which is necessary for the entrance and exit of the dirigible.

The invention is hereinafter described in detail with reference to the accompanying drawings which illustrate by way of example and diagrammatically one form of 30 the hangar embodying the invention.

Figure 1 is a view in longitudinal elevation of the improved hangar.

Fig. 2 is a plan view of the hangar illustrated in Fig. 1.

Fig. 3 is a transverse sectional view of the hangar.

Figs. 4 and 5 illustrate the different arrangements of the movable doors to constitute the outer harbors.

The hangar is constituted by four vertical girder poles a_1 b_1 carrying two main suspension girders A A' of cables or chain bars. Each of these main girders is located 45 in the same vertical plane as the girder poles a_1 b_1 of the two longitudinal sides of the hangar and have depending therefrom roof supporting main stays A'' . The ends of the main stays and the secondary and trans- 50 verse girders t , which with the braces and cover constitute the roofing of the hangar, bear upon these two main suspension girders. The weight of this roofing rests therefore entirely on these four poles a_1 a_1 55 b_1 . This roofing is made to be stable and

rigid by itself being in the form of a suspended platform. The suspended roofing being thus independent of the walls and the lateral and vertical partitions, it is sufficient in order entirely to close the hangar, to construct movable partitions or doors. This is effected by providing vertical partitions or doors p p_1 with transverse partitions connected at e mounted on rollers g and being adapted to travel on rails v v_1 arranged in 60 such a manner as to create by suitably disposing these partitions or doors, an outer harbor which is necessary for the exit and entrance of the dirigible. The plan view of these rails, in Figs. 4 and 5 in particular, 65 represents by way of example the general disposition in one direction or the other of the articulated doors constituting the longitudinal walls of the hangar. The rails v and v_1 supporting the movable partitions or 70 doors are arranged longitudinally of the hangar on both sides thereof and extending beyond the ends of said hangar bending outwardly therefrom in a gradual curve, as 75 clearly shown in the plan view of Fig. 2. It will be obvious from this construction 80 that when the side partitions or doors are moved longitudinally of the hangar in either direction, they will follow the course of the track and form the necessary wind 85 breaks or harbors desired.

Dependent upon the direction of the wind, upon the exit or entrance of the dirigible, one or other of the series of doors is manipulated; thus for a wind blowing at right 90 angles to the wall between the girder poles b b_1 of the hangar (that is to say in the direction of the arrow shown in Fig. 5), the doors between the girder poles a a_1 , may be opened either partly at each side to the positions a' a'_1 , or entirely on one or both sides 95 to the positions a'' and a'_1 a''_1 . The same conditions would apply if the wind were blowing at right angles to the wall between the girder poles a_1 a instead of between b b_1 100 that is to say in the opposite direction.

If, however, the wind is blowing in a direction at right angles to the transverse wall between the girder poles a b (see Fig. 4) the doors between the girder poles a_1 a 105 will be moved along the entire length of rails to the positions a' a'' and the doors between the girder poles b b' to the positions b' b'' .

By this means a large outer harbor is pro- 110

vided permitting the easy maneuvering of the dirigible both in entering and leaving the hangar.

From the above description it is apparent 5 that by forming the hangar in this manner the exit or entrance of a dirigible on one side of the hangar or the other in accordance with the direction of the wind is facilitated. Movable doors may be placed on 10 every side if desired but in practice, it will be found sufficient to provide movable doors on the two longitudinal sides of the hangar only.

I claim:

15 A hangar for dirigibles comprising four separate girder poles, main girders extending between and suspended at each end from the girder poles, a roof or cover supporting

main stays depending from said girders for suspending the roof or cover, rails forming 20 tracks arranged on each side of said hangar and curving outwardly from the longitudinal axis thereof, and displaceable side walls which are supported on said rails independently of the poles, suspension girders 25 and cover, and are movable to positions to form harbors at the ends of the hangar, but adapted to coöperate with the roof or cover when in a normal position to form a complete housing or hangar.

30

In testimony whereof I affix my signature, in presence of a witness.

CDT. GASTON LEINEKUGEL LE COQ.

Witness:

CHAS. P. PRESSLY.
